(57) **CLAIM**

We claim the ornamental design for a structural member for a rack, as shown and described.

DESCRIPTION

FIG. 1 is a perspective view of a structural member for a rack, showing our new design;

FIG. 2 is a right side elevation view of the structural member for a rack;

FIG. 3 is a left side elevation view of the structural member for a rack;

FIG. 4 is a rear elevation view of the structural member for a rack;

FIG. 5 is a front elevation view of the structural member for a rack;

FIG. 6 is a rear perspective view of the structural member for a rack; and,

FIG. 7 is a top plan view of the structural member for a rack of FIG. 1, the opposite bottom plan view being the same as the top plan view.
